CONTROL CONSOLE FOR FAUCETS AND THE LIKE

Donald W. Grasmehr, Edison, Ohio, assignor to The
Tappan Company, Mansfield, Ohio, a corporation of
Ohio

Filed Jan. 13, 1965, Ser. No. 83,405

Term of patent 14 years

(Cl. D91—3)

FIG. 1

FIG. 2

FIG. 3

FIG. 4

FIG. 5

FIG. 1 is an oblique perspective view of a control console for faucets and the like embodying my new design, with the faucet being shown in broken lines and included for illustrative purposes only;

FIG. 2 is a side elevation thereof as viewed from the left of FIG. 1, with the opposite side being a mirror image of this illustrated side;

FIG. 3 is a top plan view thereof;

FIG. 4 is a front elevation of said control console;

FIG. 5 is a rear elevation of the console;

FIG. 6 is a further oblique perspective view of a control console for faucets and the like embodying my design and comprising another embodiment of the invention, with the faucet similarly shown here in broken lines and included for illustrative purposes only;

FIG. 7 is a side elevation of the console of FIG. 6 as viewed from the left of FIG. 6, with the opposite side being a mirror image of the side here illustrated;

FIG. 8 is a top plan view of the FIG. 6 embodiment;

FIG. 9 is a front elevation of the FIG. 6 console; and

FIG. 10 is a rear elevation of the FIG. 6 console.

I claim:

The ornamental design for a control console for faucets and the like, as shown and described.
